COMBINATION LOCK

Andy A. MacMillan, Los Angeles, Calif.

Application November 13, 1945, Serial No. 628,095

1 Claim. (CL 70—293)

1

My invention relates to combination locks and it has for a purpose the provision of a combination lock characterized by its structural simplicity, low cost of manufacture, and easy mode of operation, all to render it adaptable particularly, although not necessarily, to safety boxes in which valuable papers, money and jewels are adapted to be stored.

It is also a purpose of my invention to provide a combination lock which embodies a plurality of locking units mounted on the box lid for independent operation, manually to occupy predetermined positions in respect to a common keeper situated on the inner side of the box, and by which the keeper is engaged to lock the box lid against opening, and other positions in which the keeper is disengaged to unlock the lid and permit opening of the box.

A further purpose of my invention is the provision of a combination lock of the above described character, wherein each locking unit comprises a rotatable latch member on the inner side of the box lid and a turnable dial on the outer side of the box lid by which the latch member can be manually moved to a keeper releasing position as determined by a prescribed dial numeral when brought into registry with a symbol located on the lid, thereby requiring that the dials for all of the locking units be positioned in a certain numerical combination to locate the releasing positions for all of the latch members, in order that such members may be caused to disengage the keeper to effect unlocking of the box lid.

I will describe only one form of combination lock embodying my invention, and one practical adaptation thereof, and will then point out the novel features thereof in a claim.

In the accompanying drawings:

Fig. 1 is a view showing in top plan one form of combination lock embodying my invention as applied to a safety box, with a portion of the lid being broken away to show the hinge mounting for the lid.

Fig. 2 is a sectional view taken on the line 2—2 of Fig. 1.

Fig. 3 is a fragmentary horizontal sectional view taken on the line 3—3 of Fig. 2.

Having specific reference to the drawings my invention in its present embodiment is shown applied to a box or receptacle of conventional construction, and which in the present instance, comprises a body 15, including a rear wall 16 upon which the rear edge of a lid 17 is mounted by means of a hinge 18 to occupy open and closed position with respect to the body, and in closed

2

position the forward edge of the lid is in engagement with the upper edge of the front wall 19 of the box. This box may be constructed of any suitable material such as metal or plastic, and in its present use is adapted for the storing of legal papers, currency, and the like.

The combination lock embodying my invention comprises a keeper K which, in the present instance, is in the form of a metal or plastic bar secured at its lower edge to the inner side of the front wall 19 by means of rivets 20 arranged at intervals along the length of the bar. It will, of course, be understood that any suitable means may be employed for securing the keeper bar to the front wall of the box. The keeper bar is bent transversely to provide an offset portion 21 in order to clear the front edge of the lid 17 when the latter is in closed position. Beyond the offset portion the bar extends upwardly where its upper edge is curved inwardly to form a lip 22 which may be made coextensive in length with the keeper bar.

The combination lock also includes a plurality of locking units mounted on the lid 17 and each of which is adapted to engage the lip 22 of the keeper bar K for locking the lid in closed position on the box. Each unit is designated generally at T and as the construction, mode of operation, an adjustment of the several units is identical a description of one unit will suffice for all.

The several locking units are arranged at intervals along the length of the lid 17 at the points corresponding to bosses 23 formed on the under side of the lid adjacent its forward edge.

Each locking unit comprises a latch member 24 rotatively mounted at the lower side of the respective boss 23 by a dial 25 having a shank 26 rotatable in a suitable opening in the lid and boss and fixed to the latch member by means of a fastener 27, which, in the present instance, is in the form of a screw threaded into the shank 26. The dial 25 is disposed to the upper or outer side of the lid for access by the operator, and provided on its upper face with an annular series of numerals 28 ranging in denomination from zero to 9.

The latch member 24 is in the form of a disc of metal or other suitable material, with a segmental portion removed to provide a straight edge 24a. Likewise, is the corresponding boss 23 cast to provide a straight edge 23a, but in so doing a slightly raised portion 23b beyond the straight edge, remains. To accommodate this raised portion so as to permit complete closing of

the lid 17, the keeper bar K is formed with a recess 29.

Each locking unit T may be moved to lock or release the lid through rotation of the dial 25. To lock the lid the dial is turned until the respective latch member 24 is in a locking position in which the peripheral portion of the member extends beneath the keeper bar lip 22. However, to release the lid the dial must be turned until the straight edge portion 24a is opposite the keeper bar and in which position the member is displaced from beneath the bar.

For visibly indicating the releasing position of any one latch member 24 for any one locking unit, the upper surface of the lid 17 is provided with a locating symbol 30 which may be in the form of an arrow positioned adjacent the periphery of the respective dial 25. It is by means of this symbol operating in conjunction with a particular number 28 that the circumferential position of the dial corresponding to the releasing position of the latch member can be determined provided, of course, the particular dial numeral is diametrically opposite the straight edge 24a as previously known. For example, if the numeral 6 is opposite the straight edge when the latter is adjacent and parallel to the keeper bar lip, the operator knows that the latch member is in releasing position and, hence, free of the latch bar.

If one desires to change the particular dial number necessary to locate the releasing position of the latch member, all that is required is to turn the dial and latch member relatively so that a different number is opposite the straight edge 24a. This can be readily accomplished by loosening the screw 27 to permit turning of the latch disk on the screw.

When considering the locking units collectively, it becomes manifest that the latch member 24 for all of the units must be individually turned to releasing position in respect to the common keeper bar K before the lid can be opened. Also, that by individual and circumferential adjustment of the latch members on the screws any desired numeral combination can be selected to

which the dials have to be individually turned in relation to the locating symbols, to effect release of the lid. Manifestly, this gives virtually unlimited number combinations.

5 Although I have herein shown and described only one form of combination lock embodying my invention, it is to be understood that various changes and modifications may be made therein without departing from the spirit of my invention, 10 and the spirit and scope of the appended claim.

I claim:

In a combination lock for locking two members together wherein one of said members is formed with a series of apertured bosses on one side thereof, a plurality of lock units mounted on said one member and corresponding in number to said bosses, each lock unit including a shaft mounted to rotate in one of said bosses, a dial fixed to one end of said shaft on the side of said one member opposite said bosses, a disk having a straight edge cut out portion fixed to the shaft on the other side of said one member, and an elongated keeper bar secured along one longitudinal edge thereof to the other of said members, said keeper bar having a curved lip portion along its other longitudinal margin over which said disk is adapted to extend except at the straight edge cut out portion thereof, said curved lip portion having recesses therein adapted to receive a portion of said bosses.

30 ANDY A. MACMILLAN.
